UNITED STATES PATENT OFFICE.

WILLIAM S. KELLEY, OF SMITHVILLE, NEW JERSEY, ASSIGNOR TO THE
H. B. SMITH MACHINE COMPANY, OF SAME PLACE.

WIRE SPOKE.

SPECIFICATION forming part of Letters Patent No. 292,562, dated January 29, 1884.

Application filed May 13, 1882. (No model.)

To all whom it may concern:

Be it known that I, WILLIAM S. KELLEY, a citizen of the United States, residing at Smithville, in the county of Burlington, State of New Jersey, have invented a new and useful Improvement in the Manufacture of Wire Spokes, which improvement is fully set forth in the following specification and accompanying drawings, in which—

10 Figure 1 is a side elevation of spoke-making machinery embodying my invention. Fig. 2 is a top or plan view thereof. Fig. 3 is a front view enlarged of the draw-plate. Fig. 4 is an end view thereof. Fig. 5 is a section in line x x , Fig. 3. Figs. 6 and 7 are views of the spokes as produced.

Similar letters of reference indicate corresponding parts in the several figures.

My invention relates to improvements in 20 spokes for vehicle-wheels and machinery for making the same.

The objects of the invention are, first, to produce a spoke maintaining all of the natural strength of the material of which it is composed; and, second, to provide means for readily and uniformly producing the spoke.

Referring to the drawings, A represents the double butt-ended spoke embodying my invention, which may be formed of steel, brass, &c., the same having the ends a thicker than the main length b of the spoke, said ends being the original thickness of the wire, the length b being reduced by drawing or other suitable means. One end is screw-threaded, 35 so as to be fitted to the hub, and the other head will be headed on the tire, it being seen that I produce a simple, durable, and inexpensive spoke, which advantages exist in the wheel. The reduction of the body b of the 40 spoke does not destroy the strength of the material of which said length or body is composed, and the ends of the spoke being of greater thickness, are admirably adapted for connection with the hub and tire of the wheel. Furthermore, spokes having the features hereinbefore set forth may be readily produced 45 uniform in all respects.

B represents a divided draw-plate formed of two blocks of steel or other suitable metal, on

the inner face of which is formed the half of a draw-opening, C C, (one or more,) the complete opening being of conical form for the wire to be drawn. The two blocks or sections of the plate are connected by springs D D, which hold them apart, so that larger-sized wire may be admitted and passed between the blocks, and the power of the spring is overcome, so that the blocks close by the screw E of the frame or housing F, within which the plate is fitted, said housing being supported on 6 the table G of the machine which makes the spokes.

H represents the frame of said machine, and J the driving-shaft, which is provided with a clutch, K, one part of which is connected to 65 the pinion L, which is mounted loosely on said shaft J. Gearing with said pinion L is a spur-wheel, M, whose shaft is mounted on the frame H, and carries a drum, N, which projects partly above the table G, and has secured to it the 70 cord or chain P, with which the tongs Q are connected, the spur-wheel M having a portion of its periphery untoothed, being what is known as a "mutilated" wheel. It will be noticed that the periphery of the drum N and 75 the chain P are in a line coinciding with the longitudinal direction of the opening C of the draw-plate, and that the clutch K is operated by a treadle, R, or other convenient means. Rising from the table is a cutter, S, and journaled to said table is a screw, T, which is fitted to an ear or boss, T', on the housing or frame F of the draw-plate, whereby the latter may be adjusted to different lengths of spokes 80 to be formed.

The operation is as follows: The wire to be converted into spokes is preferably run from a reel and a piece of proper length cut therefrom. The draw-plate is opened and the wire introduced into the opening C, the end of the 90 wire toward the tongs protruding from the draw-plate sufficiently to leave the length of one end, a , of the spoke, the draw-plate being closed by the screw F, and said end of the wire grasped by the tongs. The clutch is now 95 operated, and the power applied to the shaft J causes the wheel M to be rotated, and the drum N then winds the chain P, whereby the

wire is drawn through the plate, thus forming the reduced part *b* of the spoke. As soon as the untoothed part of the wheel *M* reaches the pinion *L* the former is rendered inoperative, whereby the winding of the chain is immediately stopped and the drawing of the wire ceases, thus leaving the remaining length of the wire undisturbed, whereby the opposite end, *a*, of the spoke is produced. The clutch is operated as soon as the wheel *M* is stopped, whereby the pinion *L* is free to permit the chain to be run back, in order that the tongs may grasp a fresh piece of wire, the wheel *M* returning to its first position. When a fresh piece of wire is cut and the draw-plates are opened, said piece is introduced into the openings *C*, the plates are closed, the wire is grasped by the tongs, the treadle *R* operated, and the clutch engaged, whereby the wheel *M* is again rotated, so that the piece of wire is drawn, and by the other manipulations another spoke is produced. The operations are repeated, the result being spokes of uniform dimensions.

It is evident that for the purpose of opening or separating the blocks of the draw-plate 25 the screw *E* may be swiveled to one of the blocks, so that while the screw is employed to close the plate it may also move one block from the other, and thus open the plate.

Having thus described my invention, what I 30 claim as new, and desire to secure by Letters Patent, is—

A double butt-ended wire-drawn spoke attenuated between the butts by supplementary die-drawing, in contradistinction to a spoke 35 butt-ended by upsetting the ends or by making the butt-ends of separate pieces, and presenting continuously throughout the fiber unbroken found in the wire from which it has been made.

WM. S. KELLEY.
